Filed Mar. 10, 1958, Ser. No. 720,480

5 Claims. (Cl. 84—171)

This invention relates generally to combined musical instruments. More specifically, this invention relates to a combined accordion and electric organ.

The music industry has been active for many years in trying to produce a variety of combined musical instruments. Specifically, much effort has been directed to combining additional instruments with keyboard instruments because two or more of these instruments could be played conveniently through a common keyboard. In most of these combinations the actuating elements were combined in one instrument but the sound producing elements of the different instruments were in separate casings. In other words, one instrument would have an attachment that was capable of actuating the sound producing elements of a second instrument removed from the first instrument. This was especially true with keyboard instruments that were used in conjunction with instruments whose sounds were produced by electrical apparatus.

The problem with the above described combined musical instruments is that two separate casings were required with some sort of a connection usually electrical, between the instruments. This made a bulky combination that was awkward to play and expensive to build. Furthermore, if an electrical connection was used, a large number of wires were required between the accordion and the second instrument. Usually, these wires were carried from one casing to the other in the same casing or conduit and interference often resulted, causing inferior tones to be produced. When playing such an instrument the operator's activity was limited because he was in effect tied to the second instrument even though the first instrument was portable.

This invention overcomes the problems encountered with the above described combined instruments by calling for a combined musical instrument in which the sound producing elements of both instruments are entirely contained within a single casing. This instrument makes it possible for the player to produce a tremendous variety of tones and often gives him greater freedom of movement when playing. Furthermore, the instrument is more compact, easier to handle and less expensive than comparable prior art combinations requiring two separate instruments.

Therefore, it is the object of this invention to provide a new and improved combined musical instrument.

Another object of this invention is to provide a new and improved musical instrument which combines an accordion with a second musical instrument.

Another object of this invention is to provide a new and improved accordion-electric organ that is contained within a single unit.

Another object of this invention is to provide a new and improved accordion-organ that is compact and easy to play.

Another object of this invention is to provide a new and improved combined accordion-organ in which the organ and accordion can be played simultaneously or independently.

Objects and advantages other than those set forth above will be apparent from the following description when read in connection with the accompanying drawings, in which:

5 Fig. 1 is a top view of the accordion-organ of this invention;

Fig. 2 is a cross sectional view of the accordion-organ taken along the line II—II of Fig. 1, specifically showing the interior of the treble side of the instrument;

10 Fig. 3 is an enlarged sectional view taken along the line III—III of Fig. 1;

Fig. 4 is an enlarged top view of the keyboard of the instrument with some of the keys removed, showing the switches for energizing the elements of the organ;

15 Fig. 5 is a schematic circuit diagram of the organ portion of the instrument; and

Fig. 6 is an enlarged view of a mounting block with the organ components mounted thereon.

The combined musical instrument of this invention is illustrated in the drawings in connection with a standard accordion and an electrical organ although the invention is applicable to any keyboard instrument in combination with any electrical sound producing elements. Specifically both the accordion and the organ are played

25 through a common keyboard and may be played individually or simultaneously.

Referring more specifically to the drawings, the combined musical instrument 10 of this invention comprises an accordion 11 having a casing including a treble side

30 13, a bass side 14, and an expandable bellows 15 intermediate the sides and enclosing the space therebetween. The accordion 10 is provided with a keyboard 17 comprising a plurality of keys 18 pivotably mounted on a block 19 attached to the base plate 20. The keys 18

35 closely resemble the keys of a piano and have extension 22 for sounding a note of the accordion. Specifically, each extension 22 has a flap valve cover 23 positionable adjacent a valve opening 24 in a valve plate 25. Each valve opening 24 is associated with a corresponding reed, not shown, on one of the reed blocks 29. The accordion

40 11 operates in the usual way well known in the art in that the keys 18 are depressed and pivot the extensions 22 to allow air to escape through a selected reed and its associated valve opening 24 to thereby sound the desired note. Suitable springs 31 are positioned between each key 18 and the base plate 20 to urge the keys to their normal position as shown in Fig. 3 and to hold the valve covers 23 against the valve plate 25 to prevent any air leakage through the openings 24 when the key is not being depressed.

45 Adjacent to the valve plate 25 is a slide plate 33. The slide plate 33 is actuated by controls 34 mounted on the treble side 13 of the accordion casing 12. The controls 34 move the slide plate 33 to selectively block certain of the valve openings 24 and thereby render that

50 portion of the accordion inoperative. The slide plate 33 can be moved to block all the valve openings 24 thereby rendering the entire accordion inoperative to permit the playing of the organ 36 independently through the accordion keyboard 17. The slide plate 33 is operatively connected to the control 34 by means of suitable

55 cams and levers. Such an arrangement is well known in the music industry and most accordions are equipped with such a device to selectively control the number of reeds to be made operative at any one time. U.S. Patent

60 No. 2,527,912, J. Burgari, illustrates such an arrangement in connection with a piano accordion.

65 The electric organ 36 is best explained in connection with the circuit diagram shown in Fig. 5. A source of power is illustrated at 37. Connected to the source of power is a master tone generator 38. The tone generator can be any suitable tone generating device but prefer-

ably is a transistor circuit. The master tone generator 38 produces a high frequency wave. For purposes of illustration, assume that the tone generator 38 produces a wave having a frequency of 880 cycles per second. Frequency dividers 39 are connected in circuit with and synchronized by the tone generators in a manner well known in the art. Although three frequency dividers 39 are shown, it is understood that any number of dividers may be used depending on the variety of sounds it is desired to produce. Each frequency divider 39 can divide the wave frequency received by any desired amount but preferably each frequency divider divides the frequency of the wave it receives in half. For example, the wave entering the first frequency divider 39 has a frequency of 880 cycles per second and the wave leaving the divider has a frequency of 440 cycles per second. The reason for dividing the frequency of the waves in half is that the sound produced by the wave divided in half is exactly one octave lower than the sound produced by the wave from which it is divided. The dividers can also be any suitable electric tone generating device but preferably they are transistor circuits. Transistor circuits are used for the master tone generator and the frequency dividers to facilitate the mounting of these elements within the accordion casing.

Each of the frequency dividers 39 and the tone generators 38 are connected to contacts 41 positioned beneath the switch means 42. The switches 42 are positioned to engage the contacts 41 and thereby selectively throw into the circuit the frequency dividers 39 and the tone generators 38. To accomplish this, the other end of the switches 42 are connected to bus bars 45 and 46 or other suitable connections which are in turn connected to the voicing unit 47. The voicing unit combines and filters the waves received to produce a desired tone sound wave. This wave is directed to an amplifier 48.

In the preferred instrument illustrated in the drawings, the accordion 11 has forty-one keys 18 and the organ 36 has twelve master tone generators 38, each of which is divided down three or more times by frequency dividers 39 so that there is a separate organ note for each key 18.

Both the accordion and the organ are designed to be played through the keyboard 17. To this end the switches 42 are mounted beneath each accordion key 18 for selectively connecting an associated note producing circuit of the organ to suitable filtering and amplifying means. The switches are either made of spring material or are provided with spring means for keeping the switch in a non-contacting position as shown in Fig. 3. Any number of switches may be positioned beneath each key but preferably as shown in the drawings, a double switch whose contacts 50 are separated by insulation 51 is mounted beneath each key. The free ends of contacts 50 of the switches 42 are positioned to engage contacts 41 when their associated key is depressed. The other ends 52 of the contacts 50 are connected in any suitable manner to bus bars 45 and 46. The bus bars 45 and 46 are separated in space and extend longitudinally beneath the keyboard 17 and are connected to the voicing unit 47. The contacts 41 are wired to corresponding master tone generators 38 and frequency dividers 39 such as shown in Fig. 3. The tone generators 38 and the frequency dividers 39 are in turn connected to a source of power through the medium of the jack 53 and its associated electric cord 54.

The voicing unit 47 may be any of the suitable units well known in the art and embodies tone filter circuits such as Formant filters for combining and blending the waves received from bus bars 45 and 46 and producing the desired tone. To this end the voicing unit 47 is provided with a plurality of filters, not shown, and associated controls 56 mounted on the treble side 13 of the accordion casing 12. The controls 56 direct the waves from bus bars 45, 46 through selected filters to produce sounds resembling the sounds produced by string, flute, horn and reed instruments as well as ordinary organ tones.

These controls 56 can also be used to silence the organ in the event that it is desired to play the accordion independently of the organ. This is accomplished by filtering the wave sufficiently to render them inaudible. The tones emanating from the voicing unit 47 may be directed to the amplifier 48 through the medium of the wire 58, the jack 53 and the electric cord 54.

One of the features of this invention is that the tone producing elements of the second instrument, in the preferred embodiment the electric organ 36, are mounted within the casing of the first instrument shown as the accordion 11. To accomplish this in the preferred instrument a space 60 within the treble side 13 of the accordion casing is provided for receiving the electrical sound producing elements of the organ 36. Since the accordion is a wind instrument, it is preferred that the space 60 for receiving the electric elements is enclosed such as by sides of the casing 12, the partition 61, and the cover 62 to assure that there is no air leakage through the valve plate 25. As shown in Figs. 2 and 3, this space 60 extends along the valve plate 25 between the last reed block 29 and the side of the treble casing 13 of the casing 12.

Positioned within this space 60 in any suitable manner are a plurality of mounting blocks 64 on which the electrical sound generating elements of the organ 36 are mounted. As illustrated, twelve spaced apart blocks 64 are provided. Each block 64 has mounted thereon a master tone generating transistor circuit 38 and its associated frequency divider circuits 39. After the mounting blocks 64 are positioned in the space 60, the elements on the block are connected to their corresponding contacts 41 beneath the switches 42 and to the power source, not shown, through the jack 53.

The voicing unit 47 is also mounted within the accordion casing to provide a combination musical instrument in which all the sound producing elements are positioned within the accordion casing. Specifically, as shown, the voicing unit 47 may be mounted within the treble side 13 of the casing 12 just beneath the control knobs 56.

When playing the instrument 10 the keys 18 may be depressed to produce the sounds of the accordion 16 and the organ 36 simultaneously. As a key 18 is depressed, it pivots extension 22 which in turn moves flap cover 23 to release air through valve opening 24 to play an associated reed on one of blocks 29. At the same time, the key depresses switch 42, causing it to contact the contacts 41 and thereby selectively operate its associated tone generating organ circuit. If it is desired to play the accordion independently, the controls 56 are adjusted to render the organ inaudible. If it is desired to play the organ independently, the controls 34 are actuated to move the slide plate into a blocking position to render the accordion inoperative.

Although but one embodiment is illustrated and described, it will be apparent to those skilled in the art that various changes and modifications may be made therein without departing from the spirit of the invention or from the scope of the appended claims.

What is claimed is:

1. In combination with the treble side of an accordion having the usual reed blocks and keys for actuating the same, electric switches operatively associated with at least some of said keys, said switches being in circuitry with a tone generator for producing current oscillations used in the production of musical tones, said tone generators being located in the said treble side of said accordion, whereby an amplifier and loud speaker may be separately connected to said circuitry to produce musical tones.

2. In combination with the treble side of an accordion having the usual reed blocks and keys for actuating the same, electric switches operatively associated with at least some of said keys, said switches being in circuitry with master tone generators and frequency dividers for pro-

ducing current oscillations used in the production of musical tones, said master tone generators and frequency dividers being located in said treble side of said accordion, whereby an amplifier and loud speaker may be separably connected to said circuitry to produce musical tones.

3. The combination of claim 1 in which said tone generators and said frequency dividers are transistor circuits.

4. The combination of claim 1 in which said tone generators and said frequency dividers are mounted on blocks removably mounted within said treble side of said accordion.

5. In combination with the treble side of an accordion having the usual reed blocks and keys for actuating the same, an electric switch operatively associated with each key, said switches being in circuitry with a tone generator and frequency dividers for producing current oscillations used in the production of musical tones, tone filters in

circuit with said generators and dividers, said tone generators, frequency dividers and tone filters being located in said treble side of said accordion, whereby an amplifier and loud speaker may be separably connected to said circuitry to produce musical tones.
